UNITED STATES PATENT OFFICE.

EDWIN S. TIMMONS, OF CHICAGO, ILLINOIS.

AIRSHIP.

1,144,570.

Specification of Letters Patent. Patented June 29, 1915.

Application filed June 12, 1911. Serial No. 632,548.

To all whom it may concern:

Be it known that I, EDWIN S. TIMMONS, a citizen of the United States, residing at Chicago, in the county of Cook and State 5 of Illinois, have invented a new and useful Improvement in Airships, of which the following is a specification.

My invention relates to improvements in air-ships of the heavier-than-air type; and 10 my objects, generally stated, are to provide a construction of air-ship of the type referred to by which ships of relatively large proportions, with their supporting planes bearing an equal, or substantially equal, 15 ratio to the increase in weight of the structure without impairing its stability, may be provided; to provide a construction in which the various elements thereof, such as the carrier, main planes, balancing planes, 20 guiding planes, engine-propellers, and other elements, may be mounted on the ship in a manner to render them stable and capable of resisting to the desired degree the stress and strains to which they are subjected in use, and to so arrange the supporting 25 planes with relation to the propeller or propellers as to cause the latter, when the ship is in flight, to operate against a field of air in normal condition, as distinguished 30 from the swirling, eddying currents of air artificially produced by planes, engines, cars and operators over, under or in front of the propellers as is commonly the case in air-ships as hitherto provided; and to 35 avoid the discharge of the air, displaced by the propeller, against the main planes, cars, engines or operators, with consequent production of head resistance to the movement 40 of the plane, as is the case with the present type of aeroplanes wherein the propeller is in front of the plane or planes; to so arrange the elements of the ship-structure 45 that the vertical rudders thereof will have an augmented grip on the air and thus serve to render the ship very sensitive, or responsive, to the helm, and minimize danger of skidding of the ship when turning, and, furthermore, in this connection, to provide for 50 the turning of the ship by rudders at both its front and rear ends to permit of the effecting of rapid and accurate turning of the ship; to provide the various elements of the ship, such as the main planes, balancing and steering planes and the propeller en- 55 veloping structures of such form as to permit them to be constructed from the mini-

mum amount of material and still possess the desired rigidity of structure required to render them resistant to the strains to which they are subjected in use; to provide 60 horizontal rudders on the ship and operating means therefor by which they may be set to extend either in the same or opposite directions as desired and propellers which may be set at different angles relative to the 65 car, whereby by manipulating the planes and the propellers the head resistance offered to the air by these rudders and the main planes may be varied, thus permitting the ship to not only be maintained on a 70 substantially even keel when rising and descending, but permitting the speed of the ship in descending to be arrested to such an extent as will permit of an easy landing, and rendering unnecessary, as in ascending, 75 the relatively long run upon the ground required with prior constructions before they start to ascend; to provide a construction of air-ship in which sufficient weight will be presented at its marginal edges to prevent 80 the ship from responding quickly to forces tending to destroy the equilibrium thereof, thereby augmenting the stability of the ship in the air; to provide a rigid construction of car; to provide means on the ship 85 which will operate to prevent impairment to the latter and minimize discomfort to the occupants of the ship when the latter is brought to the ground; and to provide an arrangement of car and propellers therefor 90 whereby the minimum amount of resistance is offered to the car when the ship is in flight.

My invention is illustrated in the accompanying drawings, in which—

Figure 1 is a plan view of an air-ship constructed in accordance with my invention. Fig. 2 is an enlarged section taken at the line 2 on Fig. 1 and viewed in the direction of the arrow. Fig. 3 is an enlarged section taken at the line 3 on Fig. 1 and viewed in the direction of the arrow. Fig. 4 is an enlarged, broken, view showing one of the plurality of combined caster-wheel and skid-devices with which the ship is equipped. Fig. 5 is a view in front elevation of the construction shown in Fig. 4. Fig. 6 is an enlarged section taken at the line 6 on Fig. 4 and viewed in the direction of the arrow. Fig. 7 is an enlarged, perspective, view of the frame-work of the car as I prefer to provide it. Fig. 8 is a plan

95

110

- view of one end of the frame-work of the car showing how it is connected to one of the struts of the ship, this view being taken substantially along the line 8 on Fig. 7. 5 Fig. 9 is a section taken at the line 9 on Fig. 1 and viewed in the direction of the arrow. Fig. 10 is a plan view of a portion of the car and the propellers connected therewith, a portion of the top of the car being removed. 10 Fig. 11 is a plan view of one of the pair of main planes employed, a portion of the covering of the upper side of the plane being removed. Fig. 12 is a section taken at the line 12 on Fig. 11 and viewed in the direction of the arrow. Fig. 13 is a view in elevation of a construction of tensioning device which may be interposed in each of the wires operating as braces for the construction. Fig. 14 is a plan view of the rear 15 horizontal rudder-plane, with certain portions thereof shown in section, the better to disclose the manner of pivoting it on the frame of the ship. Fig. 15 is a view in elevation of one of the four similar vertical rudder-planes employed. Fig. 16 is a view, 20 in the nature of a diagram, of the propellers and their enveloping frames showing the manner of operating the frames to set the propellers. Fig. 17 is a plan view of a section of the outer ring of the main structure of the ship, showing the manner of coupling together the sections forming this ring. Fig. 18 is a perspective view of a lever-device through the medium of which the 25 balancing planes at opposite sides of the ship are operated either in unison or independently of each other. Fig. 19 is a perspective view of the ship, in the nature of a diagram, showing the arrangement by which 30 the balancing planes at opposite sides of the ship may be operated. Fig. 20 is a view in side elevation, in the nature of a diagram, showing the mechanism for controlling the tilting of the front and rear balancing 35 planes, or horizontal rudders, either in unison or independently of each other. Fig. 21 is a view in side elevation of the operating levers for the cables shown in Fig. 20 for controlling the tilting of the front and rear 40 horizontal planes; and Fig. 22, a plan view, in the nature of a diagram, of the vertical rudders and means for controlling the simultaneous operation thereof. 45 The main frame of the ship and that 50 which affords the stability required, comprises an outer endless member 25, preferably in the form of a ring, formed of wood, steel tubing or of any other suitable material formed preferably of sections 26, 55 which are united together at their abutting ends by coupling devices 27; an inner annular series of vertically-disposed struts 28 which are spaced apart; a carrier arranged 60 axially of the ring 25 and by preference 65 being a car, such as that represented at 29, which is constructed in a manner herein-after described, and tensioning members, preferably wires, some of which connect with the member 29 at a point central of the ring 25, and with the upper and lower 70 ends of the struts 28 and the ring 25 at different points about the circumference of the latter, and others of which connect together adjacent struts 28. 75 In the particular arrangement shown, the 80 car 29 is provided at its top and bottom with rings 30 and 31 to which wires 32, 33 and 33^a are respectively connected at their inner ends, the wires 32 being connected with the upper ends of the struts 28 and the wires 33 85 and 33^a being connected with the lower ends of these struts, which latter are, preferably, of considerably greater height than the distance between the rings 30 and 31. From both the upper and lower ends of the struts 28 wires 34 extend to the ring 25 to which latter they are secured. The struts 28 are connected together by wires 28^a which extend diagonally in opposite directions from the top and bottom of each strut 28 to the 90 adjacent struts 28, and by wires 28^b and 28^c connecting these struts together at their upper and lower ends, respectively, as represented in the drawings. Each one of the wires 28^a, 28^b, 28^c, 32, 33, 33^a and 34, as well 95 as all of the other wires employed in my improved construction and hereinafter referred to, is provided with a tensioning device, such as the turnbuckle represented at 100 35; for placing all of the wires under the desired tension for rendering the structure, which in its nature closely resembles a wire-spoke wheel, rigid and in trued condition. 105 The car represented at 29 may be of any desirable construction. It is preferred, however, that it be pointed at its opposite ends as indicated in the drawings and that it be constructed with frame-work as illustrated in Fig. 7 and hereinafter described and supported from diametrically-opposed struts 28. 110 The construction of car shown in Fig. 7 115 comprises a series of rectangular shaped frames 36 spaced apart and braced at their corners by blocks 37 and a central frame 38. The central frame for the car is considerably heavier than the frames 36 as the rings 30 and 31 are connected to its top and bottom members, the frame 38 being formed with an extended base 39 to which cross-braces 40 connecting with the top of the 120 frame 38, are attached. 125 The frames 36 and 38 are connected together at their corners by cables 41, 42, 43 and 44, these cables converging at their opposite ends and being connected with the upper and lower ends of posts 45, these cables extending beyond the posts and being connected with turn-buckles 46 carried by diametrically-opposed struts 28, whereby upon tightening these turn-buckles, the ca- 125

bles 41 to 44 inclusive may be placed under the desired tension for rendering the structure rigid, the rigidity afforded by the cables last referred to being augmented by a 5 net work of wires which extend at angles to the cables 41, 42, 43 and 44, and connect with diagonally-opposed corners of the frames, and cross-wires extending about the top, 10 sides and bottom of the car-structure as represented. The frame-work of the car thus provided may be covered with any suitable material 29^a for inclosing the car, as for instance fabric, light metal, wood or any other suitable material, and a flooring, (not 15 shown) may be secured to the bottom members of the frames 36 and 38.

In the construction illustrated, I provide a pair of sustaining planes 47 which, by preference, are carried by those of the diametrically-opposed struts 28 which are directly at opposite sides of the car 29 as 20 illustrated in Fig. 1. Each of these planes is preferably formed of a series of concentric rings 48 spaced apart and made of 25 wood or any other suitable material, these rings being connected together by cross-braces 49 as illustrated in Fig. 11. The rings 48 are arranged concentrically of the struts 28 which they surround and have secured to them at preferably equal distances 30 about their circumferences radiating wires 50, some of which extend upwardly and others downwardly to collars 51 on the surrounded struts 28, these collars being provided 35 preferably at the top and bottom of the struts and of a number corresponding to the number of rings, whereby the wires radiating from these sleeves to the rings do not in any way interfere with each other. 40 The frames of the planes 47, thus provided, are covered both on their upper and lower sides with any suitable material, such as fabric, as indicated at 52 and 53, respectively, it being desired that the spaces afforded 45 between the rings, braces and the coverings 52 and 53 be filled with any suitable, relatively light, material 54, such as cork, for stiffening the surfaces of the planes and preventing bellying thereof, and where the 50 material 54 is lighter than water, prevent sinking of the ship in the latter in case of accident. The wires connecting the rings 48 with the struts 28 as stated, in practice, would each be provided with a tensioning 55 device, such as that represented at 85, and the several wires connecting these rings with the struts would be tensioned to such respective degrees as would cause the planes 47 to extend downwardly at a slight angle 60 from front to rear as represented in Fig. 12 for a purpose well known in the art.

Located between the main planes 47 and the opposing portions of the ring 25 are horizontally-disposed balancing planes 55 65 which are of circular shape as represented

in Fig. 1 and of the same construction as the planes 47, excepting that instead of supporting the rings forming the main framework of the planes 55 from certain of the non-movable struts 28 as explained of the 70 planes 47, these rings are supported by wires 56 radiating from the upper and lower ends of movable struts 57, the planes 55 being pivotally connected to the outer rings 48 and with the adjacent portions of the 75 ring 25 at points in alignment with the struts supporting the planes 47, as indicated at 58 and 59, respectively (Fig. 2), to permit the planes 55 to be tilted on an axis transverse to the line of flight of the machine. The planes 55 thus provided at each 80 side of the machine and beyond the main planes 47 are thus free to be turned upon their pivots 58 and 59 for setting them at any desired angle relative to the car, desirable mechanism for accomplishing this purpose being hereinafter described.

At the front and rear of the ship, I provide horizontally-disposed planes 60 and 61, which, in effect, operate as rudders for controlling the raising and lowering of the ship. The planes 60 and 61, which are alike in construction and so far as their framework and covering therefor are concerned 90 are identical with the planes 55, are carried 95 directly by the ring 25 which extends across these planes and carries opposed sleeves 62 rigidly secured to the ring 25 and affording bearings for sleeve-members 63 carried by the frame-work of the planes 60 and 61, as 100 clearly represented in Fig. 14, it being preferred that the connections of these planes with the ring 25 be forward of the center of these planes, whereby there is a tendency 105 of the planes, unless restrained, to swing to a position in which they present merely edgewise resistance to the air.

At opposite sides of the car 29 and adjacent to its forward and rear ends, I provide front and rear vertical rudders 64 and 65, 110 respectively, these rudders, by preference, being located in line with the space between the car and the main planes 47, and pivoted upon certain of the struts 28 as represented in Fig. 1. The rudders 64 and 65, so far as their construction is concerned, are identical with the planes 60 and 61, and are pivoted to the struts 28 forward of their centers as illustrated in Fig. 15, whereby the 115 tendency of these rudders is to normally present edgewise resistance only to the air, though it will be understood that when they are turned on their supports, by mechanism hereinafter described, to cause them to extend at an angle to the path through which the ship moves, they will operate to cause 120 the ship to be deflected in its course.

The propellers for driving the ship are illustrated at 66, these propellers being located at opposite sides of the car 29 and in 130

the spaces between the latter and the main planes 47. In the arrangement shown, the propellers are provided with sleeve-extensions 67 carrying sprockets 68, the propellers being journaled on non-rotary shafts 69 between spaced collars 70 on the latter, as represented in Fig. 10. The shafts 69 are axially and rigidly connected, through the medium of radiating wires 69^a, with rings 71 which surround the respective shafts 69 and are pivoted at opposite sides, as indicated at 72 and 73, to the outer rings 48 of the adjacent planes 47 and bearing members 73^a on the car 29, respectively, whereby the rings 71 and the parts carried thereby may be turned relative to the planes 47 and the car to set the propellers at any desired angle with relation to these planes. The propellers may be driven in any suitable manner as through the medium of sprocket-chains 74 which engage with the sprockets 68 on the propellers and with sprockets 75 secured to the separate drive-shafts 76 of the engines 77 located in the car and of any desirable construction, the engines, in the arrangement shown, operating to drive the propellers in opposite directions.

As is usual in air-ship constructions of this type, rolling supports are provided for permitting the ship to run along the ground before rising and after descending, my improved construction in this respect affording, in combination with wheels, skidding devices for reducing the strain upon the wheels and augmenting the stopping of the ship when in engagement with the ground.

My improved wheel-supports for the airship comprise a plurality of wheels 78 journaled in forked members 79, provided with curved extensions 80 and pivoted intermediate their ends to studs 81 projecting laterally from sleeve-members 82 pivoted between collars 83 on the lower ends of certain of the struts 28, it being preferred that one of such wheel-devices be provided on the strut to which the rear end of the car is secured and two of these wheel-devices be provided at the front end of the ship on the struts next adjacent to the strut to which the front end of the car is attached. The levers 79 are connected at their upper ends with the lower ends of coiled springs 84 secured at their upper ends to rigid collars 85 rigid on the struts 28 carrying these levers, as illustrated in Fig. 4, the tension of the springs 84 being such as to cause the levers 79 to be held in a position in which the wheels 78 only contact with the ground when the ship is at rest or moving over the ground under normal conditions, but permit the wheels 78 to be deflected to the position illustrated by dotted lines in Fig. 4, in which the skidding extensions 80 of the lever 79 are moved to a position for engaging with the ground, when the ship is mov-

ing over rough ground or violently strikes the ground in descending.

In operating the ship, it is desirable that the planes 55, 60 and 61, as well as the rudders 64 and 65, be adjusted on their supports to different positions for permitting equilibrium of the ship to be maintained, and to effect rise and descent of the ship on even keel, as well as to steer the ship for causing it to follow a desired course, and to this end I provide means whereby these planes and rudders may be controlled by an operator, or operators, in the car, the following being a description of means which may be employed for this purpose: Referring to the matter of the control of the planes 60 and 61, I provide adjacent to the seat for the operator, as for instance that represented at 86, a pair of levers 87 and 88, these levers being fulcrumed intermediate their ends as represented at 89 and 90 respectively. The lever 87 is connected above and below its fulcrum 89 to wires 91 and 92 which extend to the upper and lower ends respectively of the strut 93 of the plane 60; 90 and the lever 88 is connected above and below its fulcrum 90 with wires 94 and 95 which connect with the upper and lower ends, respectively, of the strut 96 of the plane 61, the wires 94 and 95 passing over pulleys 97 secured at any desired points on the car. Pivoted to the lever 87, as indicated at 98, is a connecting bar 99, which is adapted to be releasably connected with the lever 88 either above or below its fulcrum 90 or disconnected therefrom as desired. By this arrangement, the operator, assuming that the connecting bar 99 is disconnected from the lever 88, may control the setting of the planes 60 and 61 independently of each other by rocking their respective levers 87 and 88 on their fulcrums, or by connecting these levers together through the medium of the bar 99, the planes 60 and 61 may be caused to turn in the same direction or in the opposite direction when either one of the levers 87 or 88 are operated, depending on whether the bar 99 is connected with the lever 88 above or below the fulcrum 90, as will be manifest.

The means for controlling the setting of the planes 55 comprises a post 100 secured to the car in front of the seat 86 and supporting oppositely-extending horizontally disposed members 101 and 102, each of which is independently hinged to the post 100, as represented in Fig. 18, whereby they may be rocked upon the post independently of each other, though they may be releasably connected together as desired, for permitting them to swing upon the post 100 as a unit, through the medium of a bar 103 pivoted, as indicated at 104, to the member 101 and adapted to enter beneath a clip 105 secured on the member 102.

Connected with the outer end of the member 101 are upwardly-extending cables 106 and 107 which pass over pulleys 108 and 109 on the car, the cable 106 thence passing over 5 a pulley 110 on the ring 25 to the upper end of the strut 111 of the plane 55 at the right-hand side of the machine to which it is secured, this cable thence passing around a pulley 112 on the ring 25 and about pulleys 10 113 and 114 on the car, from which this cable extends and connects with the end of the member 101. The cable 107 extends from the pulley 109 to a pulley 115 on the car and thence to a pulley 116 on the ring 15 25, from which pulley this cable extends to the lower end of the strut 111 of the plane 55 at the right-hand side of the machine, and to which it is secured, this cable thence passing around a pulley 117 on the ring 25 20 and a pulley 118 on the car from which last-named pulley the cable extends to the member 101 to which it is connected. The member 102 is connected up with the plane 25 55 at the left-hand side of the machine through the medium of cables 119 and 120 which pass over pulleys on the car and ring 25 and connect with the hub-section 121 of this plane 55 for connecting it with the member 102 as described of the wires 106 30 and 107.

It will thus be understood that, assuming the connector 103 to be out of engagement with the clip 105, the operator, by rocking either one of the members 101 and 102, may 35 cause the respective planes 55 controlled thereby to be tilted in either direction as desired and independently of the other one of the planes 55, or if it is desired that these planes be operated simultaneously and in opposite 40 directions for the purposes well-known in the art, the operator, by securing the members 101 and 102 together, through the medium of the bar 103, may produce such manipulation that when the members 45 101 and 102 are connected together as stated, the swinging of the one downwardly will raise the other, and thus the planes controlled thereby will be swung upon their pivots in opposite directions.

50 The mechanism for controlling the turning of the rudders 64 and 65 comprises a foot-lever 122 pivoted, as indicated at 123, to the car forward of, and adjacent to, the seat 86, (it being desired that this lever be 55 operated by the foot of the operator) cables 124 and 125 which are connected to the opposite ends of the lever 122 and extend over pulleys 126 and 127 to the rudder 64 at the left-hand side of the machine, these cables 60 being connected with the frame-work of this rudder and at opposite sides of the strut 28 on which this plane is pivoted; cables 128 and 129 which are connected with the left and right-hand ends, respectively of the lever 122 and extend over pulleys 130 and 131

on the car to the rudders 64 at the right-hand side of the ship, these cables being connected with the frame-work of this rudder at opposite sides of the strut to which it is pivoted; cables 132 and 133 which are connected with the left and right hand ends respectively of the lever and extend rearwardly to pulleys 134 and 135, respectively, on the car and thence to the plane 65 at the left-hand side of the ship to opposite sides 75 of which these cables are connected as explained of the cables controlling the rudders 64; and cables 136 and 137 which connect, respectively, with the left and right hand ends of the lever 122 and pass over pulleys 80 138 and 139 respectively and connect with the frame-work of the rudder 65 at the right-hand side of the machine, at opposite sides of the strut 28 to which it is pivoted, as described of the rudder 64. By providing the cable connections between the rudders 64 and 65 and the lever 122 as described, the turning of this lever upon its fulcrum simultaneously turns all of the rudders 64 and 65, the rudders 65 turning in the opposite direction to that in which the rudders 64 turn, whereby these rudders supplement each other in performing the function of steering the ship.

As hereinbefore stated, the propellers 66 95 by being mounted in the frames of which the ring 71 forms a member, are capable of being turned for setting them relative to the main planes 47, and as desirable means for controlling the setting of these propellers, I 100 provide those illustrated in Fig. 16 of which the following is a description: At any suitable point on the car, preferably within easy reach of the operator occupying the seat 86, I provide a horizontally-disposed lever 140 105 fulcrumed between its ends to the car as indicated at 141. To one end of this lever are connected cables 142, 143, 144 and 145, the cable 142 extending over pulleys 146, 147 and 148 secured to the ship in any desirable manner, and thence to one of the rings 71 to the upper end of which it is connected. The cable 145 extends about pulleys 149 and 150 and connects with the last referred to ring 110 at its lower portion. The cables 143 and 144 pass over pulleys 151, 152, 153 and 154, respectively, and connect at the top and bottom of the ring 71 forming a part of the frame-work of the other propeller. It will be manifest that by providing the mechanism described for setting the supports of the propellers, the propellers may be set simultaneously with relation to the planes 47 by operating the lever 140, for accomplishing a result hereinafter explained.

115 It will be noted from the foregoing that my invention, as to its more particular features, is based upon the principle underlying a wire-spoke wheel and that this principle forms a basis for not only the main 120 130

frame of the ship, but also for the main planes, front, rear and side balancing planes, rudders and surrounding supports for the propellers, and that by such construction not only is the structure rendered exceedingly rigid, but the maximum rigidity commensurate with the weight of material used is afforded, and minimum head resistance offered in relation to bulk of material used. Furthermore, by providing the endless frame-member encircling the ship, namely the ring 25, and having it connected with the other parts of the structure as described, the entire structure from one side to the other is braced in such a manner that it affords, to the maximum degree, resistance to strains exerted against it in use. Furthermore, the ring 25 being of appreciable weight and forming the marginal element of the frame-work, operates to prevent the ship from quickly responding to gusts of wind striking its planes as the inertia of the ship to be overcome is relatively great. It will also be noted that the car, struts 28, outer ring 25 and the wires connecting these parts together form the main frame-work of the ship and, as hereinbefore stated, presents an exceedingly rigid structure, upon which the main planes, balancing planes and rudders, as well as the propellers, are carried, which produces a structure possessing a high degree of stability.

Another advantage afforded by a ship constructed on the principle stated is that of resisting strains to which it might be subjected in case of careless manipulation, or by accident, causing the ship to strike the ground at its outer margin. In such a case the danger of impairment to the ship is minimized as the strain to which it would be subjected is equalized more or less throughout the structure instead of exerting concentrated leverage upon any one part.

The combining in an air-ship of the type
stated of propellers which are settable with
relation to the main planes and balancing
planes provided forwardly and rearwardly
of the propellers is of advantage, in that
the head resistance afforded by the main
planes as well as head resistance at both
ends of the ship may be controlled for pro-
ducing sharp ascent from the ground and
corresponding descent while maintained on
a substantially even keel, thus avoiding an
undue length of run on the ground before
the ship rises, permitting sharper descent
and avoiding a long run on the ground
after landing.

The feature of spacing the planes 47 from the car in the horizontal plane and locating the propellers between the car and planes, namely in a position where the planes, engines, operators, etc., do not extend either in front, above or below the propellers, the latter in the operation of the ship operate

upon air in its normal condition as distinguished from the swirling, eddying currents of air caused by the resistance of engines, planes, etc., that are in the path of suction of propellers located behind or between the planes, and thus the propellers are capable of gripping the air to the maximum degree, and their full power is rendered effective. Furthermore, by locating the propellers as stated, the air displaced by the propellers, when the latter are operating, is not forced against a sustaining plane, engine, operator, car, or like obstruction, as is common in structures as hitherto provided, where the propellers are located in front, and thus the creation of undue head resistance by the planes and undue back-pressure on the propellers is prevented.

Another advantage of locating the propellers, as stated, in channels between the car and planes 47, is that of causing the air sucked into the propellers to move under such suction-action substantially parallel with the inclined sides of the front of the car and thus reduce head resistance from the car. 90

What I claim as new, and desire to secure by Letters Patent, is—

1. In an air-ship, the combination of frame-work formed of a central member, an endless curved member surrounding the central member and spaced therefrom, a series of upright struts surrounding said central member and located in the space between the latter and said endless member and tensioning members connected with said central member and radiating therefrom and connected with the struts toward their opposite ends and with said endless member to form a wheel-like structure, and a sustaining plane and means for driving the ship operatively connected with said frame-work, for the purpose set forth. 95 100 105

2. In an air-ship, the combination of frame-work formed of a central member, a ring surrounding the central member and spaced therefrom, a series of upright struts surrounding said central member and located in the space between the latter and said ring and tensioning members connected with said central member and radiating therefrom and connected with the struts toward their opposite ends and with said ring to form a wheel-like structure, and a sustaining plane and means for driving the ship operatively connected with said frame-work, for the purpose set forth. 110 115 120

3. In an air-ship, the combination of a carrier, frame-work comprising an endless, curved member surrounding the carrier and spaced therefrom, upright struts encircling the carrier between the latter and said endless member and tensioning members operatively connected with the carrier and radiating therefrom and connected with said 125

struts toward their opposite ends and with said endless member, and a plane and propelling mechanism operatively connected with said frame-work.

5. 4. In an air-ship, the combination of frame-work formed of a central member, an endless curved member surrounding the central member and spaced therefrom, a circular series of upright struts surrounding said central member and located in the space between the latter and said endless member and tensioning members connected with the struts toward their opposite ends and with said endless member to form a wheel-structure, and a sustaining plane and means for driving the ship operatively connected with said frame-work, for the purpose set forth. 70
10. 5. In an air-ship, the combination of a carrier, a series of struts surrounding the carrier and to certain ones of which the carrier is operatively connected, an endless curved member surrounding said struts, tensioning members operatively connected with the carrier and radiating therefrom and connected with the struts at their upper and lower ends and at their outer ends with said endless member, sustaining planes for the ship supported on certain of the struts, and means for propelling the ship. 75
15. 6. In an air-ship, the combination of a frame formed of a central member, upright struts surrounding said member, an endless curved member surrounding said struts and tensioning members operatively connected with said central member and radiating therefrom and connected with said struts toward their upper and lower ends and with said endless member, a carrier operatively connected with said frame, sustaining planes supported on certain of said struts, and propelling means on the ship, for the purpose set forth. 80
20. 7. In an air-ship, the combination of a frame formed of a central member, upright struts surrounding said central member, an endless curved member surrounding said struts and tensioning members connected with said central member and radiating therefrom and connected with said struts at their upper and lower ends and with said endless member to form a structure of wheel-like form, sustaining planes having their frame-work formed of endless curved members surrounding certain of said struts and tensioning means connected with the endless members of said sustaining planes and with the upper and lower ends of the respective struts carrying said planes, and means for propelling the ship. 85
25. 8. In an air-ship, the combination of a carrier, frame-work comprising an endless curved member surrounding the carrier and spaced therefrom, upright struts encircling the carrier between the latter and said endless member and tensioning members opera-
- tively connected with said carrier and radiating therefrom and connected with said struts toward their opposite ends and with said endless member, said carrier being connected at its opposite ends with certain of said struts, sustaining planes connected with struts at opposite sides of the carrier and spaced from the latter to afford channels at opposite sides of the carrier, propellers supported in the spaces between said planes and carrier, and means for driving said propellers. 90
30. 9. In an air-ship, the combination of a carrier, main sustaining planes supported on the ship at opposite sides of the carrier and spaced therefrom, balancing planes supported on the ship beyond said main planes, propellers supported on the ship in the spaces between said carrier and main planes, and means for driving said propellers. 95
35. 10. In an air-ship, the combination of frame-work comprising a central member, an endless curved member surrounding said central member and spaced therefrom, struts in the space between said central member and endless member and tensioning members connected with said central member and radiating therefrom and connected with the upper and lower ends of said struts and with said endless member, propeller means on the ship, sustaining planes operatively connected with said frame-work, and rudders secured to certain of said struts at the front and rear of the ship and extending into the path of the suction and blast of said propeller-means, for the purpose set forth. 100
40. 11. In an air-ship, the combination of a carrier supported on the ship, sustaining planes supported on the ship at opposite sides of the carrier and spaced therefrom, propellers supported in the spaces between said carrier and planes, means for driving the propellers, and upright rudders pivoted on the ship at the front and rear ends thereof and extending into the path of the currents of air displaced by the propellers for the purpose set forth. 105
45. 12. In an air-ship, the combination of a carrier supported on the ship, sustaining planes supported on the ship at opposite sides of the carrier and spaced therefrom, propellers supported in the spaces between said carrier and planes, means for driving the propellers, upright rudders pivoted on the ship at the front and rear ends thereof and extending into the path of the currents of air displaced by the propellers, and means for simultaneously operating the front and rear rudders in opposite directions for the purpose set forth. 110
50. 13. In an air-ship, the combination of its frame-work formed with an outer encircling member the inertia of which causes the ship to be slow in responding to sudden gusts of wind from any and all directions, 115
55. 14. In an air-ship, the combination of a carrier, frame-work comprising an endless curved member surrounding the carrier and spaced therefrom, upright struts encircling the carrier between the latter and said endless member and tensioning members opera-
60. 15. In an air-ship, the combination of a carrier, frame-work comprising an endless curved member surrounding the carrier and spaced therefrom, upright struts encircling the carrier between the latter and said endless member and tensioning members opera-
65. 16. In an air-ship, the combination of a carrier, frame-work comprising an endless curved member surrounding the carrier and spaced therefrom, upright struts encircling the carrier between the latter and said endless member and tensioning members opera-

sustaining planes supported on the ship within the confines of said encircling member and spaced apart horizontally, and means for propelling the ship interposed in the space between said planes.

14. In an air-ship, the combination of a carrier, an endless member encircling said carrier and spaced therefrom, struts surrounding said carrier, tensioning-members operatively connected with said carrier and extending radially therefrom and connected with the upper and lower ends of said struts and with said endless member, sustaining planes and means for propelling the ship, said carrier being formed of a frame-work comprising spaced frames, cables connected with certain of said struts and connecting said frames together, and a covering for said carrier, for the purpose set forth.

20 15. In an air-ship, the combination of a carrier, an endless member surrounding said carrier and spaced therefrom, a series of struts in the space between said carrier and endless member, tensioning members operatively connected with said carrier and radiating therefrom and connected with the upper and lower ends of said struts and with said endless member, sustaining planes, means for driving the ship, and cables connected with the opposite ends of said carrier and with certain of said struts, for the purpose set forth.

16. In an air-ship, the combination of a central member, an endless member encircling said central member and spaced therefrom, struts surrounding said central member, tensioning members connected with said central member and radiating therefrom and connected with the upper and lower ends of said struts and with said endless member, a sustaining plane, propellers for driving the ship, and wheels yieldingly mounted on the lower ends of certain of said struts to extend below the same, for the purpose set forth.

17. In an air-ship, the combination of its frame formed of a central member, an endless curved member surrounding said central member and spaced therefrom, a series of upright struts in the space between said central member and endless member and tensioning members connected with and radiating from said central member and connected with the upper and lower ends of said struts and with said endless member, sustaining planes supported on said frame-work, means for driving the ship, and balancing planes located in the space between said sustaining planes and said endless member and pivoted to the latter and said sustaining planes, for the purpose set forth.

18. In an air-ship, the combination of a carrier, an endless curved member surrounding said carrier and spaced therefrom,

a series of struts surrounding said carrier in the space between the latter and said endless member, tensioning members connected with and radiating from said carrier and connected with the upper and lower ends of said struts and with said endless member, sustaining planes at opposite sides of the carrier supported on certain of said struts and spaced from the carrier and from said endless member, propeller means located in the spaces between said planes and carrier, balancing planes adjustably supported on the ship in the spaces between said planes and said endless member, adjustable horizontal rudders supported on the frame-work at the front and at the rear of said carrier, and vertical rudders on the ship, for the purpose set forth.

19. In an air-ship, the combination of frame-work formed of a central member, an endless curved member surrounding the central member and spaced therefrom, a series of upright struts surrounding said central member and located in the space between the latter and said endless member, tensioning members connected with said central member and radiating therefrom and connected with the struts toward their upper and lower ends and with said endless member and tensioning members connecting said struts together, and a sustaining plane and propelling means on the ship, for the purpose set forth.

20. In an air-ship, the combination of a carrier, an endless member surrounding said carrier and spaced therefrom, a series of struts in the space between said carrier and endless member, tensioning members operatively connected with said carrier and radiating therefrom and connected with the upper and lower ends of said struts and with said endless member, sustaining planes, means for driving the ship, cables connected with the opposite ends of said carrier and with certain of said struts, and means for placing said cables under tension, for the purpose set forth.

21. In an air-ship, the combination of frame-work formed of a central member, an endless curved member surrounding the central member and spaced therefrom, a series of upright struts surrounding said central member and located in the space between the latter and said endless member, tensioning members connected with said central member and radiating therefrom and connected with said struts toward their upper and lower ends and with said endless member, tensioning members connecting together the upper and lower ends, respectively, of said struts and diagonally extending tension members connecting together the upper and lower ends of adjacent struts, and a sustaining plane and pro-

- propelling means on the ship, for the purpose set forth.
22. In an air-ship, the combination of frame-work formed of a central member, 5 an endless curved member surrounding the central member and spaced therefrom, a series of upright struts surrounding said central member and located in the space between the latter and said endless member, 10 tensioning members connected with said central member and radiating therefrom and connected with the struts toward their upper and lower ends and with said endless member, and supplementary tensioning members connected with said struts and with said endless member, and a sustaining plane and propelling means on the ship, for the purpose set forth.
23. In an air-ship, the combination with 20 a frame, of a carrier supported at its opposite ends from said frame and having its frame-work formed of spaced frames, cables extending lengthwise of the carrier connecting the frames thereof together and 25 secured at their ends to the frame of the ship, diagonal tensioning members connecting together adjacent frames at diagonally-opposed portions thereof, and a covering for said carrier.
24. In an air-ship, the combination with 30 its frame, of a carrier connected at its opposite ends with said frame and formed of a frame-work comprising spaced frames, cables extending lengthwise of the carrier and 35 connecting said frames together and at the ends of which the carrier is supported on the frame of the ship and diagonal tensioning members located at the sides, top and bottom of the carrier and connecting together the frames of said carrier at diagonally-opposed portions thereof, and a covering for the frame-work of the carrier, for the purpose set forth.
25. A frame for an air-ship comprising 45 a central member, an endless curved member surrounding said central member and spaced therefrom and formed of circumferential end-wise abutting sections and means for coupling said sections together, a series 50 of upright struts located in the space between said central member and said endless member, and tensioning members connected with and radiating from said central member and connected with the upper and lower ends of said struts and with said endless member, for the purpose set forth.
26. In an air-ship, the combination with 55 its frame-work, of horizontally-disposed planes pivoted at the front and rear of the ship and means for operating said planes 60 comprising a pair of levers pivotally supported between their ends, cables connected with one of said levers and with one of said planes, cables connected with the other of said levers and with the other of said planes, 65 and a connector carried by one of said levers at one side of its fulcrum and connectible with the other of said levers at either side of its fulcrum, for the purpose set forth.
27. In an air-ship, the combination of its 70 frame, balancing planes pivoted at the sides of the frame, and means for operating said planes comprising a pair of oppositely extending levers pivotally supported on the ship with their pivots in alinement, cables 75 connected with said planes and with said levers, and means for releasably connecting said levers together to operate as a unit, for the purpose set forth.
28. In an air-ship, the combination of 80 propeller means for driving the ship, rudders arranged at the front and rear of the ship, and means for operating said rudders independently of each other or simultaneously in the same or opposite directions, 85 comprising a pair of levers fulcrumed between their ends, separate cables connected with said levers and with said rudders, and adjustable means for connecting said levers together to cause the latter to operate in 90 the same or opposite directions as desired.
29. In an air-ship, the combination of a 95 frame, a carrier on said frame, planes on said frame at opposite sides of said carrier and spaced therefrom, and braces between said planes and carrier each formed of an endless curved member, a central member forming a propeller-seat, and a series of tensioning members arranged at opposite sides of said curved member, said tensioning 100 members being connected with said central member and with said curved member to form a wheel-like structure.

EDWIN S. TIMMONS.

In presence of—

A. U. THORIEN,
R. A. SCHAEFER.
